ELECTRICAL REDUCTION-FURNACE.

1,080,824.

Specification of Letters Patent.

Patented Dec. 9, 1913.

Application filed April 29, 1912. Serial No. 693,772.

To all whom it may concern:

Be it known that I, ROYAL E. FRICKEY, a citizen of the United States, residing at Heroult, in the county of Shasta and State 5 of California, have invented certain new and useful Improvements in Electrical Reduction-Furnaces, of which the following is a specification.

The hereinafter described invention relates to an improved "long and narrow" type of electric furnace for the reduction of metals from their ores, and has for its principal object to arrange the electrodes and connect the same to a source of electric 15 energy in such a manner as to dispose of the greater part of the energy in the charge between the electrodes, and thus balance the load on the several phases of the system, and to connect the central electrodes to two 20 phases of the system so that the current passing downward through the central electrodes is greater than that from the end electrodes, whereby the material adjacent the center and bottom of the crucible is subjected to the highest temperature resulting 25 in the crucible.

With the above mentioned and other objects in view, the invention consists in the construction and novel arrangement of 30 parts hereinafter fully described, illustrated in the accompanying drawings, and pointed out in the claims hereto appended.

To fully comprehend the invention reference should be had to the accompanying 35 drawings wherein like parts are designated by similar numbers of reference, and in which—

Figure 1 is a side elevation of a metallurgical furnace, one-half in section, disclosing the construction of the furnace and the positioning of the several electrodes therein. Fig. 2, is a transverse sectional view taken on line 2—2, Fig. 3, disclosing one of the electrodes and the bus bar connecting the same with the transformer. Fig. 3 is a top plan view of the furnace and the transformers, disclosing the electrodes, the transformers and the manner of connecting the same. Fig. 4 is a diagrammatic 50 view of the electrodes and the manner in which the same are connected to the transformers.

Referring more particularly to the drawings, the numeral 1 designates the furnace, 55 preferably oblong in shape, constructed

with the usual crucible 2, having a suitable refractory lining 3, inclosed by a metallic shell 4, and supported upon a suitable foundation 5.

The crucible is provided with the usual 60 tap holes 6, through which the molten products are removed and also with the doors 7 behind which is placed a removable lining so that an opening in the crucible is provided for starting, withdrawing or stopping a run, and suitable apertures 8 are also provided in the crucible, at the front thereof opposite the electrodes for ascertaining the position of the same.

The crucible is provided with the covers 70 9 constructed of a refractory brick or lining surrounded by a suitable metallic covering 10, and retained in position by suitable clamp arms 11, the covers being provided with a suitable opening surrounded by a 75 water jacket 11' and through the center of the jackets extend the electrodes 12', 12², 12³, 12⁴, the upper ends of which are guided by the insulated holders 13, which are connected electrically through suitable bus bars 80 14 with transformers 15.

The depth of the electrodes within the crucible is regulated by a block and tackle 13' and a winding drum 13².

Extending upwardly between the aligned 85 electrodes are the stacks 16 through which the ore charge is delivered into the crucible from any suitable source of supply as by a charging car, the stacks consisting of brick lined metallic tubes 17, supported by 90 suitable uprights 18 upon which rest suitable transversely extending I-beams 19, the upper edges of which support suitable castings carried by the outer faces of the tubes 17.

Referring more particularly to Fig. 4, the numerals 15 A—B, 15 B—C, 15 C—D, designate the secondaries of three transformers connected to a three phase system on the primary side, either in "star" or 100 "delta" fashion, in such a manner that the secondary voltages exist in the "delta" phase relation to each other, i. e. so that with equal secondary voltages and the points 20—A and 20—B, Fig. 4, joined by a conductor, the 105 usual "delta" relation would exist.

The circulation of the generated expanded gases is not essential for the successful operation of the furnace, and in its simplest form the gas generated is permitted to 110

escape upwardly through the stacks, burning in a suitable housing at the top thereof.

In the operation of the furnace, the charge-ores, carbonaceous material and fluxes are fed into the stacks 16 continuously, so that the crucible is kept full at all times. The height of the electrodes within the crucible is so adjusted that the energy delivered to the charge under these and to the bath, 10 is sufficient to reduce the fluxes; impregnate the metal with carbon and silicon; bring the bath to the temperature necessary to desulfurize and dephosphorize the metal, and to obtain the desired fluidity.

15 The position of the lower ends of the electrodes which extend into the crucible is determined from time to time by inserting a "feeling rod" in the apertures 8 in the side of the furnace, and the secondary voltage 20 to the electrodes is regulated by the usual form of regulating means, so that the load is equal on each of the three transformers and is of the desired total value.

It will be observed that as the electrodes 25 extend downwardly into the crucible for a considerable distance that there is always a conducting path of charge between the same, and the energy dissipated in the charge, comprising the path between two electrodes 30 of one phase depends upon the voltage of that phase and is independent of the voltage or load on the other phases. In addition to the above mentioned path between the electrodes there is also a path from one electrode 35 to another comprising the charge under two electrodes and the bath at the bottom of the crucible, the bath having a low resistance in comparison with the charge under the electrodes, the energy passing 40 downwardly from the ends of the electrodes is concentrated between the ends of the electrodes and the bath.

It will also be observed that in connecting the electrodes in the above mentioned 45 manner that the current passing downward under the two middle electrodes is the resultant of the current from two phases and is consequently greater than that from the end electrodes and under the condition of 50 equal voltage on each phase and equal height of the electrodes above the bath, the current under the middle electrodes is approximately 150% of and the energy dissipated approximately 225% of that under the end 55 electrodes. The current under the middle electrodes being the resultant of that from two phases, the component current in the transformers is not in phase with the corresponding voltage, however, the total energy 60 consists of that dissipated between the electrodes, which is delivered by the transformers at unity power factor, and that dissipated under the electrodes, and consequently the power factor differs little from unity.

65 As the charge descends the ore is partly re-

duced in the stacks and at the top of the crucible by the ascending generated gases formed by the reducing of ore in the crucible, but the principal reduction and carburetization of the ore takes place in the zone 70 between the electrodes; the melting and final impregnation with carbon and silicon, and the desulfurization and dephosphorization takes place in the vicinity of the ends of the electrodes, especially under the middle electrodes, as the current thereunder is greater 75 than under the end electrodes.

From the above description it will be apparent that the advantage of the present structure over the three electrode type of 80 furnace lies in the fact that a considerable portion of the total energy may be disposed in the charge between the electrodes without disturbing the balance on the several phases, which is an important feature in the 85 operation of large capacity furnaces.

Having thus fully described the invention what is claimed as new and is desired to be protected by Letters Patent is—

1. In an electrical reduction furnace of 90 the long and narrow type, the combination with a crucible, of feed stacks through which ores are fed to said crucible, end electrodes, and a plurality of middle electrodes extending downwardly through a conducting 95 charge into said crucible, said electrodes arranged in spaced relation and in alinement with each other, a source of electric energy, said electrodes being so connected to the said source of electric energy that the energy delivered by the middle electrodes is greater than that delivered by the end electrodes substantially as shown and for the purpose described.

2. In an electrical reduction furnace of 105 the long and narrow type, the combination with a crucible, of feed stacks through which charges of ore are fed to said crucible, a pair of central electrodes and a pair of end electrodes extending downwardly through a conducting charge into 110 said crucible, said electrodes arranged in spaced relation and in alinement with each other, a plurality of transformers associated with said electrodes the primary circuits of 115 which are connected to a three phase system whereby a concentrated zone of energy is produced under the central electrodes.

3. In an electrical reduction furnace of 120 the long and narrow type, the combination with a crucible, of feed stacks through which charges of ore are fed to said crucible, a plurality of electrodes arranged in a row and extending into said crucible, said electrodes connected to a three phase system 125 in such a manner that the phase-angle is 60 degrees between voltages supplied to adjacent pairs of electrodes.

4. In an electrical reduction furnace of 130 the long and narrow type, the combination

with a crucible, of feed stacks through which charges of ore are fed to said crucible, a pair of central electrodes and a pair of end electrodes extending downwardly through a 5 conducting charge into said crucible, said electrodes arranged in spaced relation and in alinement with each other, a plurality of transformers associated with said electrodes, the primary circuits of which are connected 10 to a three phase system in "star" fashion

whereby a concentrated zone of energy is produced under the central electrodes.

In testimony whereof I have signed my name to this specification in the presence of two subscribing witnesses.

ROYAL E. FRICKEY.
